UNITED STATES PATENT OFFICE.

SAMUEL ELLIS GLADDING, OF JERSEY CITY, NEW JERSEY.

SOUNDING APPARATUS FOR SHIPS.

1,020,490.

Specification of Letters Patent. Patented Mar. 19, 1912.

Application filed November 11, 1911. Serial No. 659,718.

To all whom it may concern:

Be it known that I, SAMUEL ELLIS GLADDING, a citizen of the United States, and residing at Jersey City, in the county of Hudson and State of New Jersey, have invented certain new and useful Improvements in Sounding Apparatus for Ships, of which the following is a specification, such as will enable those skilled in the art to which it appertains to make and use the same.

This invention relates to sounding apparatus for use in connection with ships or vessels of various kinds and classes, and the object thereof is to provide an improved apparatus of this class which may be easily applied and conveniently manipulated or operated at any time for the purpose of making soundings wherever necessary.

The invention is fully disclosed in the following specification, of which the accompanying drawing forms a part in which the separate parts of my invention are designated by suitable reference characters in each of the views, and in which:

Figure 1 is a side view indicating a ship and showing my improved sounding apparatus applied thereto; Fig. 2 a view at right angles to that of Fig. 1, and; Fig. 3 a view similar to Fig. 2, but showing the sounding apparatus detached and showing it partly in section and on an enlarged scale.

In the drawing forming part of this specification I have indicated at *a* the hull of a ship, and in the practice of my invention I mount in one side of said hull or at any suitable point along one side of said vessel a davit *b* from which is suspended a bar or support *c* which forms a part of the davit proper and which may be connected with said davit by a link *d* or in any other suitable way.

Mounted in the top portion of the bar *c* or in the end portion thereof adjacent to the davit is a shaft *e* on which is mounted a sprocket gear *f*, and the shaft *e* is preferably an ordinary crank-shaft and is provided with a handle *e*², but said shaft may be of any form and may be manipulated in any preferred manner.

In the lower or loose end portion of the bar *c* is another shaft *g* provided with a sprocket gear *h* which corresponds with the gear *f*, and said gears *f* and *h* are geared in connection by a drive chain *i*.

The gears *f* and *h* and the chain *i* are on the inner side of the bar *c*, and the shaft

g passes through said bar and is provided at its outer end with a tubular keeper *j* which may be formed integrally with said shaft, if desired, and as shown in Fig. 3.

Mounted in and movable longitudinally through the keeper *j* is a sounding rod *k* the ends of which are enlarged as shown at *k*² to prevent the same from passing through said keeper, and said ends are also preferably provided with cup-shaped receptacles *k*³. I also mount preferably in front of the davit *b* another davit *m* with which is connected a cord or cable *n* which is secured to or connected with the lower or free end of the bar *c* at *n*², and said cord or cable is passed loosely through an eye *m*² in the davit *m* and may be connected therewith at *m*³ in the usual manner, and by means of said cord or cable the sounding apparatus may be raised and supported in a horizontal position above the hull of the ship when not in use as indicated in dotted lines in Fig. 1 and may be lowered into operative position when desired.

The length of the sounding rod *k* is preferably about twice the draft of the ship and the length of the keeper *j* is preferably less than the draft of the ship, but the exact length of these parts may be regulated as desired with the understanding, of course, that the length of the sounding rod *k* must be greater than the draft of the ship and the dimensions of said parts must be such that when the apparatus is in use or the rod *k* in the position shown in Figs. 1 and 2, the upper end thereof will be exposed above the water.

The operation will be readily understood from the foregoing description when taken in connection with the accompanying drawing and the following statement thereof: Whenever it is desired to make a sounding, the apparatus is lowered into the position shown in full lines in Fig. 1 and the shaft *e* is manipulated so as to turn the shaft *g* and the keeper *j* in the direction of the arrows *x* in said figure, and in this operation the rod *k* turns with the keeper *j* and slides through said keeper, and the lower end portion thereof, if the ship is in too shallow water, will strike the ground and force the upper end portion thereof upwardly and this will indicate to the observer or operator the depth of the water. I also provide the shaft *e* with a ratchet *o* and mount in connection with the bar *c* a sliding lock pin *o*² which is

adapted to engage said ratchet and prevent the operation of the shafts *e* and *g* and the chain *i*, and this locking device is particularly designed for use when the sounding apparatus is in the position shown in dotted lines in Fig. 1, in which position the rod *k* may be moved back parallel with and adjacent to the bar *c* for its entire length, or approximately so.

10 In practice, the receptacles *k*³ in the ends of the rod *k* are filled with suitable adhesive material and when the ends of said rod strike the ground, particles of earth will adhere to said adhesive material and the 15 character of the earth bottom over which the ship is passing may thus be determined. It will be understood, however, that the receptacles *k*³ in the ends of the rod *k* are immaterial as far as the operation of the apparatus as a sounder is concerned, and it will also be understood that various changes in and modifications of the construction herein described may be made, within the scope of the appended claims, without departing 20 from the spirit of my invention or sacrificing its advantages, and I reserve the right to make all such alterations therein as fairly come within the scope of the invention.

It will be also understood that the operation of my improved sounder depends entirely on the fact that the keeper *j* in which the rod *k* is mounted is adapted to rotate in a vertical plane parallel with the side of the hull of the ship, or with the vertical central 35 longitudinal plane of the ship, and in this operation the rod *k* moves longitudinally in said plane and has a plunging forward and downward movement as it enters the water, and there is thus but little strain on said 40 rod and but slight tendency to break or twist the same.

Having fully described my invention, what I claim as new and desire to secure by Letters Patent, is:—

45 1. A sounding apparatus for ships adapted to be suspended from a davit and comprising a bar or support provided adjacent to one end portion thereof with a shaft having

a gear wheel and at the other end portion with a shaft having another gear wheel, a 50 drive chain mounted on said gear wheels, and said last-named shaft being also provided on the opposite side of said bar or support with a tubular keeper, and a longitudinally movable rod mounted in said 55 keeper.

2. A sounder for ships comprising a keeper adapted to be supported at one side of the ship and to rotate through a complete circle in a vertical plane parallel with the central 60 longitudinal plane of the ship and provided with a sounder rod which is movable longitudinally therethrough in both directions and in said plane.

3. A sounder for ships, comprising a support adapted to be suspended at one side of the ship and to swing in a vertical plane parallel with the central longitudinal plane of the ship and provided with a rotatable keeper adapted to turn through a complete 70 circle parallel with said plane and a sounder rod which is movable longitudinally through said keeper in both directions and in the plane of said circle.

4. A sounder for ships, comprising a support adapted to be suspended at one side of the ship and to swing in a vertical plane parallel with the central longitudinal plane of the ship and provided with a rotatable keeper adapted to turn through a complete 75 circle parallel with said plane, a sounder rod which is movable longitudinally through said keeper in both directions and in the plane of said circle, means for rotating said keeper, and means for raising said support 80 and holding it and said keeper and rod in a horizontal position.

In testimony that I claim the foregoing as my invention I have signed my name in presence of the subscribing witnesses this 9th 90 day of November, 1911.

SAMUEL ELLIS GLADDING.
